(57) **CLAIM**

The ornamental design for an endoscope sheath assembly, as shown and described.

DESCRIPTION

FIG. 1 is an isometric view of an endoscope sheath assembly; FIG. 2 is an enlarged top view of the endoscope sheath assembly;

FIG. 3 is an enlarged bottom view of the endoscope sheath assembly;

FIG. 4 is a front view of the endoscope sheath assembly;

FIG. 5 is a side view of the endoscope sheath assembly;

FIG. 6 is an isometric view of the endoscope sheath assembly with an outer casing removed to reveal a sheath;

FIG. 7 is a front view of the endoscope sheath assembly of FIG. 6;

FIG. 8 is side view of the endoscope sheath assembly of FIG. 6; and,

FIG. 9 is an enlarged bottom view of the endoscope sheath assembly of FIG. 6.

Portions of the endoscope sheath assembly shown in broken lines form no part of the claimed design.
